ARTIFICIAL SILK WASHER

Hicks Hobert McKinney, Candler, N. C.

Application July 6, 1936, Serial No. 89,231

2 Claims.

(Cl. 18—8)

The present invention relates to new and useful improvements in means for washing artificial silks, particularly rayon, and has for one of its important objects to provide, in a manner as hereinafter set forth, an apparatus of this character embodying a novel construction and arrangement through the medium of which considerable labor will be saved.

Other objects of the invention are to provide an artificial silk washing apparatus of the aforementioned character which will be comparatively simple in construction, strong, durable, highly efficient and reliable in operation, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view, showing a pair of units constructed in accordance with the present invention mounted in position in a vacuum tub, a portion only of said tub being shown in vertical section.

Figure 2 is a vertical sectional view through the lower portion of the invention.

Figure 3 is a view in horizontal section, taken substantially on the line 3—3 of Figure 2.

Figure 4 is an elevational view of the invention with the sleeve sections and cap omitted.

Figure 5 is a top plan view of the invention with the cap omitted.

Figure 6 is a view in vertical section through the upper portion of the invention, and

Figure 7 is a view in side elevation of a perforated sleeve forming part of the invention.

Referring now to the drawings in detail, it will be seen that the embodiment of the invention which has been illustrated comprises a perforated tube 1 of any suitable length, diameter and material, said tube having a tapered upper end portion 2. Fixed on the lower end of the tube 1 is an annular plate 3 from which a discharge neck 4 depends. It will be observed that the plate 3 extends inwardly and outwardly from the tube 1. The depending neck 4 fits snugly in an opening which is provided therefor in the bottom of a conventional vacuum tub 5. A gasket 6 is provided beneath the plate 3 for preventing leakage around the neck 4.

Mounted on the tube 1 is a plurality of perforated sleeves 7. As illustrated to advantage in Figure 2 of the drawings, the lowermost sleeve

7 rests on the plate 3. The lower end portion of each sleeve 7 is formed to provide an internal groove or channel 8 in which a packing ring 9 of suitable material is mounted and engaged with the perforated tube 1. The lowermost walls 10 of the grooves or channels 8 are formed to expose enough of the packing rings 9 to permit the upper ends of the subjacent sleeves 7 to engage said packing rings. In other words, the perforated sleeves 7 are mounted one on the other with the packing rings 9 providing a leak-proof joint therebetween.

At its upper end the perforated tube 1 is provided with an internal flange 11 having diametrically opposite notches or recesses 12 therein. The notches or recesses 12 are to permit the engagement beneath the flange 11 of hooks 13 on a cap 14. The cap 14 projects outwardly from the perforated tube 1 for retaining the sleeves 7 in position thereon. A gasket 15 is provided beneath the cap 14 for engagement with the uppermost sleeve 7.

It is thought that the operation of the invention will be readily apparent from a consideration of the foregoing. Any desired number of the devices may be mounted in the vacuum tub 5. During the washing operation the water or any chemical that may be used passes through the perforations in the sleeves 7 and the tube 1 and is discharged through the neck 4. Of course, the washing fluid must pass through the rayon on the perforated sleeve sections 7. It will thus be seen that the perforated sleeve sections 7 constitute what may be referred to as removable spools for mounting the rayon on the perforated tube or post 1. After the washing operation has been completed the rayon may be removed from the tub by lifting the tube 1 by the cap 14. The reduced neck 4 provides a convenient handle for the tube 1 when the rayon is being prepared for the tub.

By reason of the gasket 6 and the packing rings 9 the washing fluid can escape only through the perforations in the sleeves 7 and the tube 1. The upper ends of the sleeves 7 are rolled, as at 16, to provide seats for the packing rings 9. In Figure 1 of the drawings the rayon is indicated in dotted lines and designated by the reference numeral 17. The sleeves 7 may, of course, be of any suitable length and any desired number thereof may be mounted on the tube 1. The device protects the rayon from damage in the event that the vacuum should be broken. Also, if desired, the sleeves or spools 7 may be eliminated.

and conventional spools used on the perforated tube or post 1.

It is believed that the many advantages of an artificial silk washing apparatus constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

1. An artificial silk washer of the character described comprising a perforated tube adapted to be mounted in a fluid tank, said tube being tapered at one end and being provided at the other end with an integral annular plate extending radially outwardly thereof to provide a supporting flange and radially inwardly thereof to provide a reduced opening and said plate having a descending tubular extension in line with said reduced opening to serve both as a liquid outlet and as a handle for the said tube; a plurality of perforated sleeves removably mounted one on top of the other on the perforated tube, said sleeves being receivable only at the tapered end of the tube with the lowermost sleeve resting upon the said flange, said sleeves constituting holders for the rayon, and means on the ends of the sleeves for providing leak-proof joints therebetween, said

means including packing rings mounted on the lower ends of the sleeves, said packing rings being engaged with the perforated tube and resting on the upper ends of the subjacent sleeves.

2. An artificial silk washer of the class described comprising a perforated tube adapted to be mounted in a fluid tank, an annular plate fixed on the lower end of said tube and extending radially inwardly and outwardly therefrom, a discharge neck depending from the plate, a gasket mounted below the plate and encircling the discharge neck, a plurality of perforated sleeves removably mounted one on top of the other on the perforated tube and being greater in diameter than said tube to provide an annular space therebetween, said sleeves constituting removable holders for the artificial silk, the lowermost sleeve resting on the plate, each sleeve having its lower end portion formed to provide an internal channel, resilient packing rings mounted in the channels and engaged with the perforated tube, said packing rings further being exposed through the lowermost walls of the channels to be engaged on the upper ends of the subjacent sleeves for providing leak-proof joints therebetween, and a cap detachably mounted on the upper end of the perforated tube and engaged with the uppermost sleeve for removably securing the sleeves in position on the perforated tube.
